(57) **CLAIM**

The ornamental design for a luggage insert hanger, as shown and described.

DESCRIPTION

FIG. 1 is a front perspective view of the luggage insert hanger showing, the design of the present invention.

FIG. 2 is a front view of the present invention showing the hanger element in the extended position.

FIG. 3 is a back view of the present invention showing the hanger element in the extended position.

FIG. 4 is a right side view of the present invention showing the hanger element in an extended position.

FIG. 5 is a left side view of the present invention showing the hanger element in an extended position.

FIG. 6 is a top view of the present invention showing the hanger element in the extended position;

FIG. 7 is a bottom view of the present invention.

FIG. 8 is a back perspective view of the present invention with the ranger element in a folded position.

FIG. 9 is a front view of the present invention with the hanger element in a folded position.

FIG. 10 is a back view of the present invention with the hanger element in a folded position.

FIG. 11 is a right side view of the present invention with the hanger element in a folded position.

FIG. 12 is a left side view of the present invention with the hanger element in a folded position.

FIG. 13 is a top view of the present invention with the hanger element in a folded position; and,

FIG. 14 is a bottom view of the present invention with the hanger element in a folded position.

The dash-dash broken lines in the figures show portions of the luggage in hanger which form no part of the claimed design. The dash-dot broken lines show the boundary of the claim and form no part of the claimed design.

1 Claim, 10 Drawing Sheets
